UNITED STATES PATENT OFFICE.

GABRIEL A. BOBRICK, OF BOSTON, MASSACHUSETTS.

DESIGN FOR A SCHOOL-CHAIR.

SPECIFICATION forming part of Design No. 25,897, dated August 4, 1896.

Application filed July 2, 1896. Serial No. 597,909. Term of patent 7 years.

To all whom it may concern:

Be it known that I, GABRIEL A. BOBRICK, a citizen of the United States, residing at Boston, in the county of Suffolk and State of Massachusetts, have invented and produced a certain new and original Design for a School-Chair, of which the following is a specification, reference being had to the accompanying drawing, forming a part thereof.

10 The drawing shows in perspective a school-chair illustrating my design.

The leading feature of my design for a chair consists in a top piece concaved in the direction of its length, straight side bars extending downwardly therefrom to the seat, and short curved arms tangent to the side bars and the sides of the seat.

In the drawing the concaved top piece B is mounted near its ends on straight side bars 15 B', which extend downwardly therefrom di-

rectly to the seat A, while short curved arms A' are tangent to the side bars and extend therefrom in a graceful curve downward and forward to the sides a of the seat, to which the arms are also tangent. Convex rounds C 25 are located between the seat and back piece within the side bars, as shown.

Having fully described my invention, what I claim, and desire to secure by Letters Patent, is—

The design for a school-chair, substantially as herein shown and described.

In testimony whereof I have signed my name to this specification in the presence of two subscribing witnesses.

GABRIEL A. BOBRICK.

Witnesses:

JOHN C. EDWARDS,
AUGUSTA E. DEAN.
